UNITED STATES PATENT OFFICE

LEON J. BEEMAN, OF LANCASTER, NEW YORK

FLAG FOR RURAL MAIL BOXES

Application filed December 6, 1927. Serial No. 238,181.

This invention relates to a flag designed primarily for use in connection with rural mail boxes, one of the objects being to provide a device of this character which will be held by gravity in either of two extreme positions, namely, retracted or extended.

A further object is to provide simple and efficient means for guiding the flag during its movement to retracted or extended position.

With the foregoing and other objects in view which will appear as the description proceeds the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings,

Figure 1 is an elevation of a portion of a mail box carrying the flag in retracted position thereon.

Figure 2 is a section on line 2—2, Figure 1.

Figure 3 is a view similar to Figure 1 showing the flag moved to extended or active position.

Referring to the figures by characters of reference, 1 designates a portion of a rural mail box and a guide 2 in the form of a yoke having inturned sides is connected to the box by a bolt 3 or the like so that the guide is thus free to turn about the bolt. In this guide is slidably mounted the shank 4 of a flag 5 and an operating lever 6 is pivotally mounted at 7 on the box 1. One end of this lever 6 is pivotally connected, as at 8, to that end of the shank 4 remote from the flag 5. The other end of the lever constitutes a handle whereby said lever can be actuated readily.

The parts are so proportioned that when the flag is retracted, as shown in Figure 1, the connected end portions of lever 6 and shank 4 will rest upon a stop lug 9 which is fastened to the box 1. Another stop lug 10 is fastened to the box above the lug 9 at one

side of the shank 4 and is so located that when the lever 6 is shifted in the direction indicated by the arrow in Figure 1, it will thrust upwardly against the shank 4, cause said shank to slide longitudinally within the guide 2, 55 and swing the connected ends of the lever and shank upwardly past the dead center and against the stop lug 10. While thus located the flag will be extended laterally beyond the box as shown in Figure 3 where it will be held by gravity.

It will of course be apparent that during the actuation of the flag the guide 2 will swing about its point of connection with the box.

What is claimed is:

1. The combination with a mail box or the like, of a guide pivotally connected to said box, a lever pivotally connected to the box, a flag, a shank extending therefrom and pivotally connected to the lever and slidable within the guide, and stop means on the box at opposite sides of the lever for limiting the movement of the lever and shank when in either of two extreme positions at opposite sides of the dead center, thereby to hold the flag in either extended or retracted position relative to the box to which it is connected.

2. The combination with a mail box or the like, of a guide yoke, means for connecting the yoke to said box for rotary motion, an actuating lever pivotally connected to the box, a flag, a shank extending from the flag and slidable in and movable with the yoke, a pivotal connection between the shank and lever, and stops at opposite sides of the lever for limiting the movement of the lever and shank past a dead center in opposite directions respectively, thereby to hold the flag in either extended or retracted position relative to the box.

In testimony that I claim the foregoing as my own, I have hereto affixed my signature.

LEON J. BEEMAN.
